CLAIM

The ornamental design for a display and storage rack for hand tools, as shown and described.

DESCRIPTION

FIG. 1 is a perspective view showing my new design for a display and storage rack for hand tools, with four such racks being shown mounted to a pegboard and carrying hand tools, the pegboard and hand tools being shown for illustrative purposes.

FIG. 2 is an enlarged front perspective view showing my new design.

FIG. 3 is an enlarged rear perspective view showing my new design; and,

FIGS. 4 and 5 are right and left side views, respectively, of the rack of my new design.

The pegboard and hand tools are shown in FIG. 1 to illustrate an environment for my new design, therefore, no claim is made to the pegboard and hand tools shown in phantom lines in FIG. 1.
